UNITED STATES PATENT OFFICE.

JAMES G. JOHNSON, OF CHICAGO, ILLINOIS.

DESIGN FOR A FOOT REST AND WARMER.

55,616.

Specification for Design.

Patented July 6, 1920.

Application filed January 21, 1920. Serial No. 353,090. Term of patent 3½ years.

To all whom it may concern:

Be it known that I, JAMES G. JOHNSON, a citizen of the United States, residing at Chicago, in the county of Cook and State of Illinois, have invented a new, original, and ornamental Design for a Foot Rest and Warmer, of which the following is a specification, reference being had to the accompanying drawing, in which a perspective view of the design is shown.

I claim:—

The ornamental design for a foot rest and warmer, as shown.

In testimony whereof I affix my signature.

JAMES G. JOHNSON.
